UNITED STATES PATENT OFFICE.

JAMES A. ANDREWS AND JOHN W. HERBERT, OF BIDDEFORD, MAINE.

HUMIDIFIER.

1,316,073.

Specification of Letters Patent. Patented Sept. 16, 1919.

Application filed April 30, 1918. Serial No. 231,711.

To all whom it may concern:

Be it known that we, JAMES A. ANDREWS and JOHN W. HERBERT, citizens of the United States, residing at Biddeford, in the county of York and State of Maine, have invented a new and useful Improvement in Humidifiers, of which the following is a specification.

This invention relates to certain new and useful improvements in a humidifier and particularly to a construction especially adapted for changing and cooling the air in buildings such as mills without injury to the running of work in construction, the principal object being to provide such a device which will supply, in an efficient and rapid manner, large quantities of moist air, the humidity of which may be readily controlled.

Further, the invention resides in a force feed humidifier that may also be employed for extracting or withdrawing the foul air from the room when not acting in the capacity of a humidifier, or cooler, or a humidifier and cooler combined.

In the drawings—

Figure 1 is a longitudinal section through a portion of the improved humidifier illustrating the invention.

Fig. 2 is a transverse section on line 2—2 of Fig. 1 looking toward the air intake end of the mixing chamber of one section or unit.

Fig. 3 is a similar view on line 3—3 of Fig. 1 through the steam chamber, and disclosing the outlets from the steam and air chamber.

The structure, in its preferred embodiment, comprises a plurality of stepped units, each of which is formed by a main outer shell or pipe 1 having one end reduced to embrace the adjacent end of the next shell or pipe, as at 2.

Within the shell 1 is a hollow chamber having a longitudinally extending inclosure or mixing chamber 3, and lateral and upwardly extending wings or sections 4 that communicate at one end with the chamber 3. Diametrical outlet pipes 5 lead from the upwardly extending sections 4, and with the combined air and steam or mixing chamber 3 is connected a steam chamber 6, a pair of spaced perforated baffle plates 7 separating the two chambers. Steam is supplied

through a pipe 8 which enters through the bottom of the steam chamber, and supported above the inlet is a baffle 9 designed to be impinged by the inflowing steam for diffusing the same so as to cause it to pass through the perforated baffles in an even manner. The vapors which condense within the chambers find a ready drain through drip pipe 10.

A fan or blower 11 disposed at the large end of the humidifier shell, directs a blast of fresh air axial therein to be discharged through the small end of the structure or through the outlet pipes 5 after having first intermingled with the steam that has passed upwardly through the perforated baffles into chamber 3. The charge of air entering chamber 3 for co-mingling with the steam and the consequential outflowing humid air, is controlled by a valve or damper 12 which is mounted on a horizontal shaft 13, journaled in the respective shell, for opening and closing the end of said chamber toward the fan. By turning on handle 14 of shaft 13 the damper may be raised or lowered to either admit or shut off the air.

Disposed longitudinally within each section is a central U-shaped conductor or trough 15 by which the waters of condensation, should there be any in the main pipe, may be carried to the respective chamber 6 and thence withdrawn from the system. This trough opens through the closed end wall of chamber 3 into the space 20 for draining off all water which accumulates from time to time in the main pipe. The trough extends beyond the steam chamber 6 for the entire length of chamber 3 so that the steam, in entering said chamber 3, will be carried by the current of air away from the front end of the trough and thereby be prevented from escape into the main pipe.

In operation, steam under low pressure passes up through the sections 4 and out through pipe 5 into the room to moisten the atmosphere. The forced air supply passes through the entire length of the pipes and discharges through the smaller end. Where, however, it is desired to diffuse the steam or moisture-laden atmosphere, any one or more of the dampers may be opened, and the steam shut off or a large portion thereof, so that the air is caused to pass through chamber 3 and upwardly through the wings or sections

4 to the outlet pipes. Uniformity in the humidity of the atmosphere is controlled through the instrumentality of a thermostat or automatic expansion valve 16 arranged in 5 the steam pipe 8.

In some instances, such as when the operations in a mill are first started, the steam being shut off and the dampers all turned upwardly or in opened position, the fan 10 may be driven in a reverse direction to create a suction through all the pipes 5 as well as the main pipe which operation will efficiently relieve the room of foul atmosphere.

Thus, the atmosphere may easily be 15 changed or renewed and the humidity controlled in an efficient manner. The construction is simple and different localities may be rendered more humid than others merely by the control of the dampers.

20 Having thus described our invention, what we claim as new and desire to secure by Letters Patent is—

1. A humidifier comprising a series of stepped units, each consisting of a shell 25 opened at both ends, a fan arranged at one end of the units for forcing air axially therethrough, an internal hollow structure in each shell having a longitudinally extending mixing chamber opening at one end into the 30 shell and having oppositely extending wing conduits leading from its opposite end and discharging through the shell to the exterior, a steam chamber arranged exteriorly of the shell and communicating with the mixing 35 chambers, a steam supply pipe connected to the steam chamber, a solid baffle arranged in the latter over the steam inlet, a drip pipe leading from the steam chamber, and a U-shaped drain trough arranged in the mixing 40 chamber for conducting condensation waters from the interior of the shell to the steam chamber.

2. A humidifier comprising a series of stepped units, each consisting of a shell 45 opened at both ends, a fan arranged at one end of the units for forcing air axially therethrough, an internal hollow structure in each shell having a longitudinally extending mixing chamber opening at one end into the 50 shell and having oppositely extending wing conduits leading from its opposite end and discharging through the shell to the exterior, a steam chamber arranged exteriorly of the shell and communicating with the mixing 55 chamber, a perforated baffle interposed between the mixing and steam chambers, a steam supply pipe connected to the steam chamber, a solid baffle arranged in the latter over the steam inlet, a drip pipe leading 60 from the steam chamber, a U-shaped drain trough arranged in the mixing chamber for conducting condensation waters from the interior of the shell to the steam chamber, and dampers controlling the opened forward 65 ends of the mixing chambers.

3. A humidifier comprising a series of stepped units, each consisting of a shell 70 opened at both ends, a fan arranged at one end of the units for forcing air axially therethrough, an internal hollow structure in each shell having a longitudinally extending mixing chamber opening at one end into the shell and having oppositely-extending wing conduits leading from its opposite end and discharging through the shell to the exterior, a steam chamber exteriorly of the shell and communicating with the mixing chamber, a steam supply pipe connected to the steam chamber, means interposed between the steam inlet and the mixing chamber for diffusing the steam, and means controlling the admission of air through the forward 75 opened end of the mixing chamber.

4. A humidifier comprising a series of stepped units, each consisting of a shell 80 opened at both ends, a fan arranged at one end of the units for forcing air axially therethrough, an internal hollow structure in each shell having a longitudinally extending mixing chamber opening at one end into the 85 shell and having oppositely extending wing conduits leading from its opposite end and discharging through the shell to the exterior, and means for moistening the air passing 90 through the mixing chamber.

5. In a humidifier, a shell, means for forcing a current of air axially therethrough, a mixing chamber disposed off axis within the shell, means for controlling the admission of air from the shell into the chamber, and means for moistening the air in the chamber. 95

6. In a humidifier, a shell, means for forcing a current of air axially therethrough, a mixing chamber arranged within the shell 105 to one side of its axis, said chamber having lateral discharge passages, means for controlling the admission of air from the shell into the chamber, and means for admitting steam directly into the mixing chamber.

7. In a humidifier, a shell, means for creating a current of air therethrough, a mixing chamber communicating with the shell, means for controlling the admission of air from the shell into the chamber, said chamber being arranged within the shell and having an outlet leading through the same, a steam chamber communicating with the mixing chamber, and a foraminous partition between the steam and mixing chambers for 110 diffusing the steam as it enters the mixing chamber.

8. A humidifier comprising a series of stepped units, each consisting of a shell opened at both ends, a fan arranged at one 115 end of the units for forcing air axially therethrough, an internal hollow structure in each shell having a longitudinally extending mixing chamber arranged off center and opening at its forward end into the shell and at 120 130

its opposite end through the shell to the exterior, air-moistening means communicating with the chamber, and means controlling the passage of air through the chamber.

5 9. A humidifier for house and factory ventilation, comprising a single air-conducting shell having lateral discharge openings at longitudinally spaced points, and steam-supplying means for each discharge opening
10 to moisten the outflowing air, and means located in the vicinity of each discharge open-

ing for automatically controlling the supply of steam to said first means.

In testimony whereof we have signed our names to this specification in the presence of 15 two subscribing witnesses.
